UNITED STATES PATENT OFFICE.

EDWARD L. STORY, OF EVERETT, MASSACHUSETTS.

BUSHING FOR FEED-WATER PIPES FOR BOILERS.

1,174,297.

Specification of Letters Patent.

Patented Mar. 7, 1916.

Application filed May 29, 1915. Serial No. 31,268.

To all whom it may concern:

Be it known that I, EDWARD L. STORY, a citizen of the United States, residing at Everett, county of Middlesex, State of Massachusetts, have invented an Improvement in Bushings for Feed-Water Pipes for Boilers, of which the following description, in connection with the accompanying drawing, is a specification, like characters on the drawing representing like parts.

In some boilers of the fire-tube variety it is the practice to connect the feed water pipe which leads to the boiler from the exterior thereof to a bushing that is secured 15 in the boiler head and which projects through the latter into the boiler and then to screw-thread to the inner end of the bushing a distributing pipe which leads to the back end of the boiler and through 20 which the water is delivered to the boiler.

It is found in practice that the distributing pipe is apt to break off at the screw-threaded part thereof and drop down upon the fire tubes of the boiler. When this happens it is necessary to repair the damage 25 by first removing from the inner end of the bushing the end of the distributing pipe which is retained therein and then to screw the broken end of the distributing pipe into 30 the bushing again. This operation is a laborious one due to the fact that the removal of the end of the distributing pipe from the bushing can usually be done only by chipping the end of the pipe out and 35 also to the fact that there is very little room within the boiler in which a person may work.

It is the object of my present invention to provide a novel bushing for the feed water 40 pipe of a boiler which is so constructed as to obviate to a large extent the possibility of the distributing pipe becoming broken, and which is so constructed that if by chance the distributing pipe does become 45 broken, the broken end can be easily and quickly removed and the damage can be readily repaired.

In order to give an understanding of my invention, I have illustrated in the drawings some embodiments thereof which will 50 now be described, after which the novel features will be pointed out in the appended claims.

In the drawings Figure 1 is a sectional view showing one form of my invention; Fig. 2 is a similar view showing another em-

bodiment of the invention; Fig. 3 is a reduced section on the line 3—3, Fig. 1.

1 indicates a boiler head into which the fire flues (not shown) of the boiler are secured as usual. Inasmuch as the invention relates merely to the bushing to which the feed water pipe and distributing pipe are connected, I have not deemed it necessary to illustrate the boiler, but have contented myself with showing a portion of the boiler head 1.

2 indicates the feed water pipe which is on the exterior of the boiler and through which the feed water is delivered to the 70 boiler, and 3 indicates a portion of the distributing pipe within the boiler which communicates with the feed water pipe 2 and through which the water is delivered to the rear end of the boiler, as usual in boilers 75 of this type.

As stated above, the common practice at present is to screw the feed water pipe 2 into a bushing secured in the boiler head 1 and which projects into the interior of the 80 boiler and then to screw the end of the pipe 3 into the inner end of the bushing. This construction has the disadvantages which are set forth above.

In my present invention I provide a novel 85 form of bushing with which the feed water pipe 2 has communication and which is so constructed that the end of the distributing pipe 3 can be slipped into the inner end of the bushing and held therein by a clamp so 90 that the distributing pipe may be readily removed from the bushing or inserted in place with a minimum expenditure of time and labor. In the construction shown in Fig. 1 my improved bushing is shown at 4 and it 95 is screw-threaded into the boiler head 1, as shown at 5, the screw-threads on the bushing preferably being tapered so as to make a tight joint. 6 is a lock nut employed to assist in holding the bushing firmly in the 100 boiler head 1. The bushing extends through the boiler head 1 and has the portion 7 on the exterior of the boiler head into which the feed water pipe 2 is screwed as usual. The bushing 4 is made of considerable length 105 and projects several inches into the boiler, as shown in Fig. 1, the inner end 9 of the bushing being split at 8, as shown by dotted lines Fig. 1. This split inner end 9 is of sufficient size so as to permit the end of the 110 distributing pipe 3 to be readily inserted thereinto. Said bushing is constructed to

present a smooth bore so that the attachment of the distributing pipe thereto is made by merely slipping the pipe into the bushing instead of screw-threading it thereto. The 5 distributing pipe is firmly held in position by means of a clamping ring 10, which is shown as a split clamping ring encircling the split portion 9 of the bushing and clamped tightly thereabout by means of a clamping 10 bolt 11. It is not essential that there should be an absolutely water-tight joint between the distributing pipe 3 and the bushing 9, and the connection shown in Fig. 1 makes a sufficiently tight joint for all practical 15 purposes. Moreover, by using the construction shown the walls of the distributing pipe 3 are not reduced in thickness as they would be if threads were cut therein and, therefore, the liability of the distributing pipe 20 being weakened by corrosion is greatly reduced. Moreover, if the distributing pipe should break off near the bushing 4 and it should become necessary to remove the broken end of the pipe, this can be readily 25 done by loosening the clamping ring 10 and then removing the broken pipe end. The end of the pipe 3 may then be inserted into the split end of the bushing and clamped in place, thus repairing the damage, and all 30 this can be accomplished in a short time and with very little labor. The splitting of the end 9 of the bushing enables it to contract slightly, thus providing for firmly clamping it about the pipe 3.

35 In Fig. 2 I have shown an embodiment of my invention which is especially designed to be used in connection with boilers which are already equipped with the old construction above set forth. In this embodiment 40 the feed water pipe 2 is screwed into a bushing 12 which is screwed into the boiler head 1 from the exterior, said bushing 12 being that into which the distributing pipe 3 is usually screwed. In applying my invention 45 to this construction without discarding the bushing 12 I employ a bushing member 13,

one end 14 of which is screwed into the inner end of the bushing 12 and the other end 15 of which is split, as shown at 16, and is provided with a smooth bore of a size to 50 receive the distributing pipe 3. Said pipe 3 is clamped in the split portion 15 of the bushing 13 by means of a clamping ring 10. In equipping a boiler with my invention, as shown in Fig. 2, the distributing pipe 3 will 55 be unscrewed from the bushing 12, the bushing member 13 will be screwed into the bushing 12 and the pipe 3 then secured to the bushing member 13, as shown. In this embodiment the connection by which the distributing pipe 3 is secured to the boiler head 1 is in the form of a two-part bushing comprising the two sections 12 and 13, the latter being constructed to have the end of the distributing pipe 3 clamped therein. 60 65

While I have illustrated some selected embodiments of my invention, I do not wish to be limited to the constructional features shown.

I claim:

1. In a device of the class described, the combination with a boiler head, of a bushing secured thereto and having its inner end extending into the boiler, a distributing pipe removably clamped to said inner end, and a 70 feed water pipe connected to the exterior end of the bushing to deliver water therethrough to the distributing pipe.

2. In a device of the class described, the combination with a boiler head, of a bushing 80 secured thereto and having its inner end extending into the boiler, said inner end being split, a distributing pipe having its end slipped into the split end of the bushing, means for clamping said split end of the 85 bushing to said distributing pipe, and a feed water pipe connected to the exterior end of the bushing to deliver water therethrough to the distributing pipe.

In testimony whereof I have signed my 90 name to this specification.

EDWARD L. STORY.
